United States Patent Office

Des. 190,771
Patented June 27, 1961

190,771

BOTTLE

Charles Robert Alvey, New York, N.Y., assignor to The Clorox Company, Cincinnati, Ohio, a corporation of Ohio

Filed Dec. 27, 1960, Ser. No. 63,354

Term of patent 14 years

(Cl. D58—8)

FIG. 1.

FIG. 2.

FIG. 3.

FIG. 4.

The dominant features of the design reside in those portions shown in solid lines.

I claim:

The ornamental design for a bottle, as shown and described.
